(57) **CLAIM**

The ornamental design for a set of earphones and charging case as shown and described.

DESCRIPTION

FIG. 1 is a perspective view of an earphones of a set of earphones and charging case, shown separately to show aspects of the design that are not visible when combined, showing my new design;

FIG. 2 is another perspective view thereof;

FIG. 3 is a front elevational view thereof;

FIG. 4 is a rear elevational view thereof;

FIG. 5 is a left side elevational view of the right earphone of the set of earphones and charging case;

FIG. 6 is a right side elevational view thereof;

FIG. 7 is a top plan view of the earphones of the set of earphones and charging case;

FIG. 8 is a bottom plan view thereof;

FIG. 9 is a perspective view of a charging case of the set of earphones and charging case, shown separately to show aspects of the design that are not visible when combined, showing my new design;

FIG. 10 is another perspective view thereof;

FIG. 11 is a front elevational view thereof;

FIG. 12 is a rear elevational view thereof;

FIG. 13 is a right side elevational view thereof;

FIG. 14 is a left side elevational view thereof;

FIG. 15 is a top plan view thereof;

FIG. 16 is a bottom plan view thereof;

FIG. 17 is a perspective view of the set of earphones and charging case, shown in a closed configuration; and,

FIG. 18 is a perspective view of the set of earphones and charging case, shown in an open configuration.

The broken lines in the drawings depict portions of the set of earphones and charging case that form no part of the claimed design.
